BUILDING CORNER CONSTRUCTION

John P. Koval, Norwood, Mass., assignor to Bird & Son, inc., East Walpole, Mass., a corporation of Massachusetts

Application October 12, 1949, Serial No. 120,890

2 Claims. (CL. 20—5)

1

This invention relates to building corner construction and more specifically to preformed corner elements which may be applied to the outside of a building usually in vertical series with overlapping horizontal joints, having improved characteristics from the standpoint of economy, appearance, and sealing of the corner against rain and snow.

The corner elements of this invention are especially adapted for use at external corner junctures of building walls provided with ornamental siding panels of a type known to the art which are applied with overlapping horizontal joints exposing the lower edges of said panels, one type thereof being formed with alternating areas of differently colored adhesively affixed mineral granules giving a visual appearance of the grain of wooden shingles. These corner elements are preferably designed to carry out such wood imitation at the juncture of said walls which is not provided by many currently employed corner elements.

It has been customary in the past to use specially designed narrow metal corners either painted or mineral-surfaced to match the color of the siding panels, the use of which necessitated extremely accurate cutting of the edges of the siding panels in order that the required weathertight seal be produced at the juncture of said walls.

An object of the present invention is to provide a novel corner element of pleasing appearance which may be easily applied and does not require accuracy in cutting the edges of the siding panels to produce a weathertight joint.

A further object of my invention is to provide a corner element especially adapted to be interfitted with courses of siding panels in such manner that the joints between the corner elements are reinforced to prevent breaking off of the overlapping portions, and so interfitted as to preserve and carry out the horizontal alignment of said courses.

For the purposes of simplification and economy, the corner element of this invention may be formed with a base which is composed of fibre-board and is so constructed that the element maintains its preformed angular configuration adapting it for application to the corner of a building, and yet possesses a certain amount of flexibility, due to the absence of any metallic reinforcement, permitting the unit to conform more readily with building irregularities usually found. The term "fibre-board" is understood to include various types of composition boards as commonly used in the art.

2

For the purpose of further explaining my invention, reference is made to the following drawings, in which:

Fig. 1 is a perspective view of the novel corner of my invention;

Fig. 2 is a perspective view, partly broken away, of the corner of my invention as installed with overlapping siding;

Fig. 3 is a cross-sectional view taken on line 10 3—3 of Fig. 2, and

Fig. 4 is a cross-sectional view taken on line 4—4 of Fig. 2.

Referring to Fig. 1, the corner element 2 comprises a sheet of fibre-board with two parallel edges of unequal length and two non-parallel edges of substantially equal length bent along a line between the median points of the parallel edges at approximately a right angle to form two sides 4 and 6. A groove or rabbet 8 is formed 15 at the upper and lower parallel edges on the inside surfaces of the sides 4 and 6, said rabbet being preferably of a depth somewhat greater than one-half the thickness of the fibre-board sheet, and a length, say, of from one-half inch 20 to an inch. The outer edges 14 of the corner element 2 are at a slight angle to a line formed at the junction of the sides 4 and 6, as the upper edges 16 of the sides 4 and 6 are somewhat shorter than the lower edges 18 of said sides, for reasons 25 hereinafter more fully explained. The corner element is impregnated or coated with a material such as asphalt or resin, which waterproofs and hardens the surface, and the exposed surfaces of said element 2 including outer edges 14 and lower edge 18 are covered with an adherent surface 30 facing of finely-divided mineral matter which may be of various colors and configurations to provide the appearance of wood grain, or the like, similar to that of the siding panels.

Referring to Figs. 2 and 3, two or more corner elements 2 are used in vertical series with overlapping edges by interfitting the rabbet 8 inside the lower edge 18 of one corner element with the upper edge 16 of another corner element, so that the upper element overlaps the lower element and forms a weathertight joint. In order 40 that the vertical outer edges 14 of said corner elements may be substantially aligned to achieve a pleasing appearance, the lower edge 18 of such corner elements must be longer than the upper edge 16 of said elements so that when 45 said elements are interfitted the outer edges 14 will substantially coincide. The difference in length between the upper edges 16 of sides 4 and 6 and the lower edges 18 of sides 4 and 6 is determined by the thickness of the completed ele- 50 55

ment at the bottom of the rabbet 8 at the lower parallel edge 18 of the corner element. In general, the lower edge 18 on either side of the corner element will be longer than the upper edge 16 on either side by an amount equal to the thickness of the completed element at the bottom of the rabbet 8 at the lower parallel edge 18 of the element.

When used in conjunction with overlapping siding panels 22 having a rabbet 24 inside their lower edges 26, as shown in Figs. 2 and 4, the rabbet 8 on the inner upper edge 16 of a corner element 2 is interfitted with the overlapping edge 26 of a siding panel 22 so that the lower overlapping edges 18 of the corner elements 2 interfit as hereinbefore described are aligned with the overlapping edges 26 of siding panels 22. When thus fitted, the upper and lower edges of the corner element are reinforced against breaking and there is a minimum of free space between the parts of the corner elements and the siding panel at the horizontal joints thus preventing any danger of rain or snow entering the joint.

Since such corner elements 2 have sides of substantial width, say 4 to 6 inches, it is unnecessary to accurately align the edges of the siding panels 22, as a small amount of horizontal overlap of the corner elements 2 over the siding panels 22 will prevent rain or snow from entering the joint.

Though the corner elements of my invention have been described in terms of a corner element for use with overlapping siding panels, corner elements embodying my invention may obviously be used at greater or lesser angles than 90°, and as such would be useful in roof construction as well.

I claim:

1. A preformed building corner element comprising a sheet of fibre-board of substantially uniform thickness having sides and upper and lower horizontal parallel edges and two diverging side edges connecting the ends of said horizontal

parallel edges, the lower horizontal parallel edge being longer than the upper horizontal parallel edge and the two diverging side edges being of substantially equal length, said sheet being bent at substantially right angles substantially along a line between the median points of said horizontal parallel edges, and a rabbet on the inside surfaces of said element adjacent each of said parallel edges, the inner vertical surfaces of the rabbets being substantially parallel with the inner vertical surfaces of its corresponding side, the lowermost horizontal edge of the rabbet on each side of the median point being longer than the uppermost horizontal edge of the corresponding rabbet on each side of the median point by an amount substantially equal to the thickness of the element at the bottom of the rabbet at the lower parallel edge.

2. In combination, a plurality of identical building corner elements as claimed in claim 1 in vertical relationship with overlapping edges, in which the upper parallel edge of one of said elements is interfitted with the rabbet adjacent the lower parallel edge of another said element to underlie said lower parallel edge and provide an overlapping water seal, the inner surfaces of said elements being uniformly slanted with the lower edge of said inner surfaces being displaced outwardly from the upper edge of said inner surfaces to interfit with overlapping siding panels underlying said elements.

JOHN P. KOVAL.
